UNITED STATES PATENT OFFICE.

JOHN M. SPEER, JR., OF FORT BRANCH, INDIANA.

GRAIN-BREAKER AND GRINDING-MILL.

SPECIFICATION forming part of Letters Patent No. 291,634, dated January 8, 1884.

Application filed October 6, 1883. (No model.)

To all whom it may concern:

Be it known that I, JOHN M. SPEER, Jr., a citizen of the United States, residing at Fort Branch, in the county of Gibson and State of Indiana, have invented a new and useful Grain-Breaker and Grinding-Mill, of which the following is a specification, reference being had to the accompanying drawings.

This invention relates to machines for grinding, breaking, or reducing grain; and its object is to construct a machine in which provision shall be made for separating or grading the grain into different sizes, and for adjusting the reducing-surfaces so that at the point where the larger-sized grains are fed they shall be farther apart than at the point at which the smaller grains are fed to the said reducing-surfaces. In machines of the class referred to where no such provision is made, the smaller grains are barely broken, or not at all, while the larger grains are liable to be crushed too finely, the result being an uneven and undesirable chop, while by my improved machine a chop may be produced which will be of even quality throughout.

Referring to the drawings hereto annexed, Figure 1 is a side view of my improved machine. Fig. 2 is a rear view of the same. Fig. 3 is a top view. Fig. 4 is a transverse vertical sectional view on the line $x-x$ in Fig. 2. Fig. 5 is a longitudinal vertical sectional view on the line $y-y$ in Fig. 1.

The same letters refer to the same parts in all the figures.

A in the drawings designates a frame or casing, provided with side beams, B B, on which are mounted boxes C, forming bearings for the ends of a shaft, D, carrying the grinding-roller E, the surface of which may be either smooth or corrugated, according to the kind of work to be done. The sides of the box or frame A are provided on their inner sides with guides or bearings F for a beam, G, adapted to slide in the said bearings to and from the grinding-cylinder, as shown. To the front upper edge of said beam is securely attached an upwardly and rearwardly inclined plate, H, serving to hold the adjustable grinding-plate, as will be presently described. The rear side of the beam G has clips I, in which are journaled screws J J, working in a transverse beam, K, at the rear end of the frame. By means of the said

screws, which are provided with suitable operating-handles, the ends of the beam and of the grinding-plate supported by the same 55 may be independently adjusted with reference to the grinding-cylinder.

L designates the grinding-plate, the grinding-face of which may be either smooth or corrugated or otherwise dressed, according to the 60 kind of work to be done. Said plate, which is mounted, as shown, upon the inclined supporting-plate H, is provided on its under side with screws M M, extending through slots N N in the supporting-plate, and provided with 65 clamping-nuts O. The upper edge of the grinding-plate is provided with lugs P, in which work the adjusting-screws Q Q, the lower ends of which are journaled in plates R R at the upper edge of the supporting-plate H. By 70 means of these adjusting-screws the grinding-plate may be raised or lowered, so as to bring its lower edge above, below, or on a level with the horizontal center of the grinding-cylinder, as may be desired, with reference to the nature 75 of the material to be operated upon.

The side beams, B B, of the casing are provided with set-screws S S, which may be tightened against the ends of the supporting-beam, for the purpose of retaining the latter securely 80 in any position to which it may be adjusted.

T designates a hopper arranged above and between the grinding-cylinder and grinding-plate, and divided by vertical partitions into several compartments, U U. In the drawings hereto annexed three such compartments, 85 U U' U², have been shown, which discharge, respectively, at the ends and at the middle of the grinding-cylinder.

V is a screen mounted upon crank-arms W 90 W on top of the frame or casing, above the hopper T. The position of said screen is slightly inclined, owing to the greater length of the crank-arms at one end of the same. It will be seen that the perforations or openings in 95 the upper end of the screen, above the compartment U of the hopper, are comparatively small. Those in the middle part of the screen, above the compartment U', are somewhat larger, and those at the lower end of the screen, 100 above the compartment U², are larger still. It follows that the screen will be graded according to the number of compartments in the hopper, the grain being thereby separated into

grades of various sizes, each size being discharged into its proper hopper. The screen is operated from a pulley, X, upon the shaft of the grinding-cylinder, which is connected by a belt or band, Y, with a pulley, Z, journaled in a suitable bearing provided at the upper end of the frame. The shaft of the pulley Z is provided with a crank-arm, A', which is connected by a pitman, B', with the screen, 10 to which a reciprocating motion may thus be imparted when the machine is operated. The chop, when reduced by the grinding mechanism, drops upon an inclined plane, C', which conveys it to suitable receptacles. Said incline is provided with partitions D', corresponding with those in the hopper, thus enabling the chop from the several hoppers to be separately inspected, enabling the attendant to set the grinding-plate properly to 15 secure the desired results.

The operation of this invention and its advantages will be readily understood from the foregoing description, taken in connection with the drawings hereto annexed. The grinding-25 plate having been properly set, power is applied, thereby causing the grinding-cylinder to revolve, and at the same time imparting a reciprocating motion to the screen. Grain is now supplied at the upper end of the latter, 30 is separated, and passes through the several divisions of the hopper to the grinding or reducing mechanism, where it is reduced to the desired degree of fineness.

This machine is simple in construction, easily 35 adjusted and managed, and efficient in operation for the purposes set forth.

I claim as my invention and desire to secure by Letters Patent of the United States—

1. The combination of the frame, the grinding-40 roller, guide-flanges upon the inner sides of the sides of the frame, a supporting-beam sliding between said flanges, clips upon the rear side of said beam, screws mounted in the rear part of the frame and journaled in said 45 clips, and set-screws mounted in the sides of the frame, and adapted to bear against the ends of the supporting-beam, substantially as set forth.

2. The combination, with the supporting-50 beam having an upwardly and rearwardly extending slotted plate, of the grinding-plate, having screws on its under side that extend

through the said slots, clamping-nuts, plates at the upper edge of the supporting-plate, lugs at the upper edge of the grinding-plate, and 55 screws mounted in said lugs and journaled in said plates, whereby the grinding-plate may be adjusted, substantially as set forth.

3. The combination of the frame, the grinding-roller, the supporting-beam, mechanism 60 for adjusting the ends of the latter independently with reference to the ends of the grinding-roller, an upwardly and rearwardly extending plate secured rigidly to the upper front edge of the supporting-beam, and the 65 grinding-plate secured adjustably upon the said inclined plate, substantially as set forth.

4. In a machine for reducing grain, the combination of a frame, a grinding-cylinder, a grinding-plate, mechanism for adjusting the 70 ends of the latter independently with reference to the grinding-cylinder, a hopper having several compartments arranged to discharge at various points of the grinding-surface, an inclined screen arranged above the 75 said hopper, and having openings of a different size above each compartment of the latter, the openings being of gradually-increasing size from the upper toward the lower end of the said screen, and suitable operating mechanism, substantially as and for the purpose set forth.

5. An organized machine for reducing grain, the same comprising mechanism for separating the grain into grades of various sizes, mechanism for feeding the separate grades to different points of the reducing mechanism, a grinding-cylinder, a grinding-plate, mechanism for adjusting the ends of the latter independently with reference to the grinding-cylinder, an inclined delivery-plane, and vertical partitions upon the latter, whereby separate compartments are formed to receive the chop from various points of the reducing mechanism, substantially as and for the purpose 95 set forth.

In testimony that I claim the foregoing as my own I have hereto affixed my signature in presence of two witnesses.

JOHN M. SPEER, JR.
